UNITED STATES PATENT OFFICE.

CHRISTIAN MARIUS LAURITZEN, OF CHICAGO, ILLINOIS.

SEPARATOR.

No. 863,189.

Specification of Letters Patent.

Patented Aug. 13, 1907.

Application filed February 11, 1905. Serial No. 245,273.

To all whom it may concern:

Be it known that I, CHRISTIAN MARIUS LAURITZEN, a citizen of the United States, residing at Chicago, in the county of Cook and State of Illinois, have invented certain new and useful Improvements in Separators, of which the following is a specification.

My invention relates to improvements in deflecting mechanism and has for one of its objects the regulation of the admission of air into a separator.

10 A further object is to provide an adjustable pneumatic separator which may be simply adjusted to separate material of different degrees of fineness, as may be required.

These and such other objects as may be hereafter described are attained by my invention, certain embodiments of which are illustrated in the accompanying drawings, in which—

Figure 1 represents a sectional view of a separator with my deflecting mechanism in place. Fig. 2 is a horizontal plan view on the line 2—2 of Fig. 1, looking in the direction indicated by the arrows. Figs. 3 and 4 represent details showing deflecting vanes set at various angles. Fig. 5 is an enlarged detail of a portion of Fig. 2. Figs. 6 and 7 are enlarged details of portions of Fig. 1. Fig. 8 is an enlarged perspective of a deflecting vane. Fig. 9 is a modified form of vane. Fig. 10 is a modified construction for shifting the vanes; and Fig. 11 is a plan view of Fig. 10.

Like letters of reference indicate like parts in the several figures of the drawings.

A A' represents the outer shell or casing and B B' the inner conical shell of the separator.

C is a pipe leading to an exhaust fan not shown.

D is the open end of the separator through which the induced current of air is brought into the separator.

E is an opening in the top of the separator through which the material to be separated is introduced therein.

F is a reinforced top of the upper portion of the inner conical shell B'.

G G are series of deflecting vanes movably mounted between the sections B B', and shifted by means of a rack and pinion H H' and a handle K.

L is a spout at the bottom of the inner shell.

45 Referring now to Figs. 5, 6, 7 and 8: the deflecting vane G as shown comprises a deflecting piece G', having a flange G² extending from its upper edge at an oblique angle to G'. One end of this flange terminates in an ear G³, while a corresponding ear G⁴ extends from the lower edge just below the ear G³. These ears are provided with bolt holes g g' registering vertically with each other. The flange G² is provided with a lengthwise extending slot G⁵. Extending around the inner conical shell are rigid rings L M between 50 which the deflecting vanes are pivotally secured by means of bolts x passing through the holes g g'. A sup-

plemental ring N is secured below the ring L. This ring has on its inner face a rack H' engaging a pinion H. Bolts O secured to the ring pass through the slots G² in the deflecting vane, limiting the circular travel 60 of the ring to the length of the slots. This movable ring is prevented from lateral or irregular movement by means of bolts P P projecting downwardly from the upper fixed ring and adapted to press against the inner circumference of the movable ring, thus limiting the 65 latter ring to a circular movement.

In Fig. 9 I have illustrated a modified form of vane G⁶ in which the deflecting piece G⁷ is vertical, and in Figs. 10 and 11 I have illustrated a modification in which the movement of the ring and the consequent 70 change of direction of the vanes is effected by means of a handle K' provided with a downwardly extending finger k, which loosely fits a hole Q in an ear or projection R on the movable ring.

Referring now to the operation of the device: By 75 means of an exhaust fan or some other suitable means, an induced current of air is caused to enter the opening D and rises in the inlet chamber a between the outer and inner shells. This current following the general direction indicated by the arrows enters the 80 return chamber in and interior of the inner shell through the openings between the vanes and thence into the pipe C. The material to be separated is introduced through the top opening E or is carried in by the air current and passes down the top B' and into the 85 inlet chamber a. The coarser material drops to the bottom and the remainder is drawn through the openings between the vanes and into the return chamber b. The vanes are preferably so arranged as that a horizontal line drawn through the faces thereof will be 90 tangent to an imaginary inner circle, and the intersection of the lines with each other will form its periphery. The size of this circle may be varied by shifting the angle of the vanes, as is clearly shown in Figs. 3 and 4. The greater the angle of the vanes or the less the openings there between, the greater the radius of the circle and conversely the less the angle and the greater the opening the less the radius of the circle. With the faces of the vanes set at an oblique angle, the resulting intersection of the continuation of the planes of these 95 faces will form the periphery of the frustum of a cone, and the interior currents of air in the return chamber b will have a gyratory motion with the greatest velocity at the face of the imaginary cone. This velocity and the length of travel of the dust laden air within the 100 cone B may of course be regulated by the manipulation of the vanes and the air laden with matter to be separated may be made to travel over a varying path with varying degrees of velocity. It will thus be seen that with a given adjustment of the angle of the vanes, the 105 material of a certain predetermined degree of fineness will be drawn into the top of the pipe C, while the 110

heavier particles will drop into the bottom of the chamber *b* and out of the spout *L*, mingling with that material dropped down the conical passage *a* and passing out at the bottom through the opening *D*, and, if desired, back into the pulverizer.

With a wider opening of the vanes, the air will have a shorter travel within the cone *B*, and the resulting material will be coarser and vice versa.

In the use of separators in connection with crushers or pulverizers, it is difficult to grade the material properly, as the material coming from the crusher is of varying degrees of fineness, while it is essential from a commercial standpoint that the resultant product shall be of a certain specified degree of fineness. The ability to accurately grade the material is the test of the efficiency of a separator. By the intelligent use of my improved device the currents of air are so regulated as that the resultant product drawn from the separator through the pipe *C* shall be of any desired degree of fineness.

While I derive the best results from the device as shown, it is practicable to have the faces of the vanes vertical, in which case the resultant position of the greatest velocity in the current in the inner casing will be the periphery of an imaginary cylinder. It is also obvious that there are many methods by which the vanes may be movably mounted and operated, and other modifications may be made in the mechanism of the structure without departing from the spirit of the invention. So also, for the purposes of my invention, the particular form of the casing *A* is immaterial. It may be conical, square, cylindrical or of any other suitable shape.

I claim:

35. 1. A separator, comprising an outer casing and an inner casing, forming inlet and return chambers, means located between said inlet and return chambers for regulating the passage of air and material from said inlet to said return chamber, said means comprising a plurality of fixed supports mounted upon said inner casing, a plurality of slotted deflecting vanes pivotally mounted upon said supports, a rotatable ring mounted adjacent to said supports and arranged to engage said vanes and provided with projections arranged to slidably engage the slots in said vanes, and means for partially rotating said ring.

40. 2. In a separator, an outer casing, an inner-casing provided with a plurality of fixed supports, a movable ring, a series of deflecting vanes operatively connected with said supports, and means whereby the movement of the ring shifts the angular adjustment of the deflecting vanes with relation to each other, said means comprising a flange on one edge of each of said deflecting vanes, said flange having a slot in its upper face, a pin rigidly fixed in said movable ring and adapted to travel within said slot.

45. 3. A pneumatic separator comprising an outer casing provided at its bottom with an opening for the admission of air and at its top with an opening for the admission of material, an inner casing having a series of vanes adjustably mounted therein to regulate the admission of material, said inner casing being provided with an opening for the discharge of coarse material, and also containing an inner discharge pipe connected with a means for inducing a current of air within the separator.

50. 4. In a pneumatic separator, the combination of an outer casing having an opening at the top for the admission of material and an opening at the bottom thereof, an inner casing having an opening at the bottom thereof and a series of openings around the sides thereof, a discharge pipe within the inner casing and extending without the

same, means tending to exhaust the inner casing through the discharge pipe, thereby inducing inwardly-directed currents through the openings in the inner casing, and adjustable means located within the inner casing for directing the currents, substantially as described.

5. A separator, comprising an outer casing and an inner casing, forming inlet and return chambers, means located between said inlet and return chambers for regulating the passage of air and material from said inlet to said return chamber, said means comprising a plurality of plates, each of said plates having a flange along one edge thereof, said flange being provided with a slot, and means for securing said plate in place comprising ears extending horizontally from the upper and lower edges of said plate, and movable means adapted to co-operate with said slots whereby said vanes may be adjusted.

6. A pneumatic separator comprising the combination of an outer casing provided with an opening in its top for the admission of material and with an opening below its top for the admission of air, a conical inner casing arranged within said outer casing and provided with an opening below its top for the discharge of material by gravity, and also provided with a downwardly and outwardly flaring top arranged to receive and scatter the material to be separated, said inner casing being provided with an opening a short distance below said conical top, means tending to exhaust air from the interior of said casings, and suitable conducting means leading from the interior of said inner casing to said exhausting means.

7. A pneumatic separator comprising the combination with an outer casing, of an inner casing and means whereby material to be separated may be introduced between said casings said inner casing being provided with an opening for the admission of material therein from between the inner and outer casings, means for exhausting air from said inner casing and thereby inducing the flow of air from between said casings into said inner casing, and adjustable means located in said inner casing and adapted to direct the inflowing air into a circular path.

8. A pneumatic separator comprising an outer casing provided with an opening for the admission of material to be separated, an inner casing having an inlet opening communicating with said outer casing, a discharge pipe leading from the inner casing, means tending to exhaust the inner casing through the discharge pipe, thereby inducing an inwardly flowing current through said inlet from the outer casing to the inner casing, and adjustable means located in said inlet for imparting rotation to said current and adapted to vary the angle at which said induced current enters said inner casing, substantially as described.

9. A pneumatic separator comprising an outer casing provided with means for the admission of material to be separated, an inner casing mounted therein and provided with an opening below its top for the discharge by gravity of certain material and provided with an inlet communicating with said inner casing above said discharge opening, a discharge pipe communicating with the interior of said inner casing above said inlet, means for exhausting said inner casing through said discharge pipe and thereby creating an induced current through said inlet into said inner casing, and means mounted in said inlet for varying the angle of entrance of said induced current into said inner casing and adapted to impart rotation to said currents.

10. In a pneumatic separator, the combination of an outer casing having an opening at the top into which material to be separated may be introduced, an inner casing having a series of openings therethrough, means for withdrawing air from the inner casing, thereby inducing inwardly directed currents through said openings, and means located within the inner casing for directing said currents, said means being adjustable and adapted to deflect the currents into a circular path.
